(57) **CLAIM**

The ornamental design for a portion of substrate for LED package, as shown and described.

DESCRIPTION

FIG. 1 is a perspective view of the portion of substrate for LED package showing our new design;

FIG. 2 is a front view thereof, the rear view being a mirror image thereof;

FIG. 3 is a left side view thereof, the right side view being a mirror image thereof;

FIG. 4 is a top plan view thereof;

FIG. 5 is a bottom plan view thereof; and,

FIG. 6 is a cross-sectional reference view thereof through VI-VI of FIG. 2.

The broken lines shown are included for the purpose of illustrating the unclaimed portions of the article and form no part of the claim.
